UNITED STATES PATENT OFFICE.

GUSTAVE M. KERTZ, OF ST. LOUIS, MISSOURI.

KNOCKDOWN CRATE.

SPECIFICATION forming part of Letters Patent No. 726,941, dated May 5, 1903.

Application filed March 13, 1902. Serial No. 97,973. (No model.)

To all whom it may concern:

Be it known that I, GUSTAVE M. KERTZ, a citizen of the United States, residing at St. Louis, in the State of Missouri, have invented 5 certain new and useful Improvements in Knockdown Crates, of which the following is a full, clear, and exact specification, reference being had to the accompanying drawings, wherein—

10 Figure 1 is a perspective view. Fig. 2 is a similar view showing the crate collapsed. Fig. 3 is a longitudinal section, and Fig. 4 is a section on line 4-4 in Fig. 3.

15 My invention relates to crates of that class known as "knockdown crates," and is especially adapted for carrying poultry; but it is applicable for many other purposes.

20 It consists in the construction and arrangement of parts hereinafter described and afterward pointed out in the claims.

25 In the drawings, 1 represents the base or bottom plate, which is preferably of wood or other suitable material, and 2 the top plate. The side and end walls 3 of the crate are constructed of flexible material, preferably canvas ducking, whereby the crate can be collapsed, as shown in Fig. 2, the flexible material being folded in between the top and bottom plates.

30 In order to hold the crate in its extended or open position, I arrange bails 4 at each end thereof, said bails being hinged to strips 5, which are secured to the upper face of bottom plate 1, as shown in Figs. 3 and 4, the 35 bails when raised to their perpendicular position being secured in grooves in strips 6, which are fastened to the under face of top plate 2.

7 indicates ventilating-openings, of which 40 there may be any suitable number, the purpose of which is obvious.

I preferably arrange two flexible handles 8, as shown, by which arrangement, when the 45 crate is being carried in the hand, it is held from tilting when the fowls move from one end to the other of the crate.

As shown in the drawings, the side and end walls are made of one continuous piece of material and fastened to the top and bottom 50 plates by tacks all around except at one end

at the top, where it is left free to form flaps to provide an opening to take the fowl to and from the crate.

9 indicates a lacing-string which is passed through a suitable eye 10 or other fastening 55 means to close the flaps, said string being tied in an eye 11.

The crate is especially adapted for the use of poultry fanciers, as it may be folded when not in use, and it may be cheaply manufactured, owing to the simplicity of its construction. However, I do not limit myself to any particular use of the crate, and I am aware that many minor changes can be made in the construction and arrangement of parts without departing from the nature and principle of the invention.

Having thus described the invention, what I claim as new, and desire to secure by Letters Patent, is—

1. In a collapsible crate, the combination of 70 the top and bottom plates, flexible side and end walls secured to and connecting said plates, means for holding the crate in an extended position, and opening in said crate, 75 flaps for closing said opening, means for securing said flaps in their closed position, and ventilating-openings in said crate, substantially as described.

2. In a collapsible crate, the combination of 80 the bottom plate 1, top plate 2, flexible side and end walls 3 secured to and connecting said plates, said side and end walls being of one continuous piece of material the ends of which form flaps to close an opening in said 85 crate, and means for securing said flaps in their closed position, substantially as described.

3. In a collapsible crate, the combination of 90 the bottom plate 1, top plate 2, flexible side and end walls 3 secured to and connecting said plates, said side and end walls being of one continuous piece of material the ends of which form flaps to close an opening in said 95 crate, means for securing said flaps in their closed position, and handles or carrying means, substantially as described.

4. In a collapsible crate, the combination of 100 the bottom plate 1, top plate 2, flexible side and end walls 3 secured to and connecting

said plates, said side and end walls being of one continuous piece of material the ends of which form flaps to close an opening in said crate, means for securing said flaps in their closed position, and bails 5 hinged to the bottom plate, the free ends of said bails being adapted to engage in grooves in the top plate,

whereby the crate may be held extended, substantially as described.

GUSTAVE M. KERTZ.
